UNITED STATES PATENT OFFICE.

SRAFFORD R. HEWITT, OF ATLANTA, GEORGIA, ASSIGNOR OF ONE-HALF TO DOWMAN-DOZIER MFG. CO., OF ATLANTA, GEORGIA, A CORPORATION OF GEORGIA.

METAL SASH-BAR.

1,329,600.

Specification of Letters Patent.

Patented Feb. 3, 1920.

Application filed September 15, 1919. Serial No. 323,703.

To all whom it may concern:

Be it known that I, STRAFFORD R. HEWITT, a citizen of the United States, and resident of Atlanta, in the county of Fulton and 5 State of Georgia, have invented certain new and useful Improvements in Metal Sash-Bars, of which the following is a specification, reference being had therein to the accompanying drawing.

10 The object of this invention is to produce metal sash bars having in manufacture and use advantages over other bars. It involves the use of straight bars which interlock with each other without bending or distortion and form a structure having broad bearing surfaces and affording unusual resistance to strains transverse to its plane.

In the accompanying drawings,

Figure 1 is a perspective view of a portion of one of a set of parallel bars used in each sash.

Fig. 2 is a similar view of one of two members forming one of the coacting set of transverse bars.

25 Fig. 3 shows the other part of the compound bar.

Fig. 4 is a perspective view showing the simple and compound bars assembled and fixed together.

30 In these views, A represents a preferably rolled metal sash bar having a plane flat body web B, provided at one margin with molded flanges C, C' to support the glass and give pleasing appearance, and having 35 along the opposite margin a narrower bead D. A member of the compound bar has a plane web F equal in width to the web B, but, preferably of approximately half its thickness. This web has at one margin 40 flanges G, G' like the flanges C, C' but at the opposite edge has no bead corresponding to D. The second member H of the compound bar has a web F' in width and thickness like F and is provided along one margin with a 45 bead I like the bead D. The flanges C, C' of the bar A are cut away at J and the like flanges or the web E are cut away at K, K' to narrow the flanges at this point and form a miter joint with the molded portion of the 50 flanges C, C'. The web E is cut away at this point, as shown at L, to receive the web B. The other web F' of the compound bar is cut away at M in like manner, but its bead is left intact, while the bead D is cut away 55 to receive it as shown at N, Fig. 1.

If the bar of Fig. 1 be dropped over the

bar of Fig. 2 in such manner that its web enters the slot L the flanges will lie in the same plane and those of each member will closely fit in the spaces formed by cutting 60 away the companion member. The web of the other part of the compound member is then placed alongside the other thin web in such position that its slot registers with the web B and is pressed down until its lower 65 edge rests upon the flanges C, C' and its bead fits in and fills the recess N formed by cutting away the bead D. The thin webs when the sash is complete are rigidly held together by spot welding, screws, or rivets, 70 the latter being shown at O. The broad, plane webs each held accurately in plane form and each having all its recesses filled with unyielding metal give great stiffness transversely, and the broad meeting faces at 75 the flange and bead joints help to give stiffness in other directions.

I have shown but one bar of each set but the sash may, of course, have any number of horizontal bars and of vertical bars and 80 each is secured in the stiles or rails of a sash by means not here important.

The sets of bars are set forth as horizontal and vertical, respectively, but obviously this is not indispensable.

85 It is especially to be noted that no part of the bars is distorted or in any way injured in assembling, that no special skill is needed for making perfect sets of assembled bars after the units are properly made, and 90 that both faces of the sash are plane and smooth. It is also important to note that the structure built up on a plane assembling table is never turned over, the parts being dropped into place, one after another, with- 95 out even momentarily deflecting any part.

What I claim is:

1. The combination with a sash bar having a plane continuous body web provided at one margin with glass-receiving flanges 100 and at the opposite margin with a bead parallel to the flanges, said flanges and bead being cut away to receive similar parts of a transverse bar, of a transverse bar having an analogous web with like flanges and 105 provided with a slot into which the web of the bar first mentioned may be dropped to bring all the flanges into the same plane.

2. The combination with a sash bar having a plane continuous body web provided 110 at one margin with glass-receiving flanges and at the opposite margin with a bead

parallel to the flanges, said flanges and bead being cut away to receive similar parts of a transverse bar, of a compound transverse bar made up of two registering body webs one having flanges at one margin and the other having a bead at the opposite margin, and both slotted to receive the web of the member first mentioned.

3. The combination with a sash bar having a plane body web slotted to receive the web of a transverse sash bar and provided along one margin with glass-receiving flanges, of a transverse sash bar having at its margins glass-receiving flanges and a bead, respectively, both flanges and bead being cut away at one point to receive similar flanges and bead of a transverse bar, and a third bar having its body web slotted like the bar first mentioned and provided at one margin with a bead to drop into the recess formed by cutting away the bead of the second bar.

4. The combination with a sash bar having a plane body web slotted to receive the web of a transverse sash bar and provided along one margin with glass-receiving

flanges, of a transverse sash bar having at its margins glass-receiving flanges and a bead, respectively, both flanges and bead being cut away at one point to receive similar flanges and bead of a transverse bar, and a third bar having its body web slotted like the bar first mentioned and provided at one margin with a bead to drop into the recess formed by cutting away the bead of the second bar, and means for rigidly uniting the webs of the first mentioned and last mentioned bars when assembled.

5. The combination with a sash bar web slotted to receive the web of a transverse bar and having at one edge flanges adapted to rest upon a plane table, of an analogous like-flanged, transverse bar with its web adapted to drop freely into the slot of the first bar and with its flanges cut away to pass over the flanges of the first bar and rest upon the table, and means for holding the two bars rigidly in place at all points.

In testimony whereof I hereunto affix my signature.

Strafford R. Hewitt.
